UNITED STATES PATENT OFFICE

HOWARD E. RICE, OF MIAMI, FLORIDA

FOLDABLE CHAIR

Application filed July 16, 1929. Serial No. 378,969.

This invention appertains to new and useful improvements in chairs and seats and more particularly to a novel foldable chair for use in dining alcoves and similar places.

5 The principal object of this invention is to provide a foldable chair which is capable of being disposed to a position against the wall or within a pocket in the wall so as to be out of the way during the operation of cleaning the floor or straightening the table.

Another important object of the invention is to provide a foldable chair of the character mentioned which will be of relatively low cost to install.

15 These and numerous other important objects and advantages of the invention will become more apparent to the reader after considering the invention as described and claimed hereinafter.

20 In the drawing:

Figure 1 represents a vertical sectional view through the novel chair construction, showing the chair in extended position.

Figure 2 represents a front elevation of 25 the novel chair structure, the same being shown in extended position.

Figure 3 represents a vertical sectional view through a wall structure showing in side elevation the improved foldable chair 30 in retracted position.

Figure 4 is a fragmentary sectional view 35 disclosing the slidable connection between the chairback and the wall taken substantially on line 4-4 of Figure 1.

Figure 5 represents a vertical sectional view through a modification of the invention showing the same in extended position.

Figure 6 is a front elevation of the modified form of the invention showing the same 40 in extended position.

Referring to the drawings, wherein like numerals designate like parts, it will be seen that 5 represents a wall of a building in which a rectangular shaped pocket 6 is formed.

45 The back and side walls of this pocket are lined with the panels 7 and 8 respectively.

The side panel 8 is provided with a longitudinally extending slot 9.

The foldable chair includes a seat section 50 10 with a cross piece 11 secured transversely

across the bottom side of its inner end portion, while a second cross piece 12 is secured to the underside of the section transversely at its intermediacy. A pair of brace bars 13-13 are employed for supporting the seat when in extended position and each of these bars has its lower end pivotally secured to the lower portion of one side panel 8 as at 14 while its upper end is pivotally connected to one end of the cross member 12.

55 A back section 15 has an extension 16 at each corner of its lower end and each of these extensions is pivotally connected to the inner end of the section 10 as at 17. A cross member 18 extends transversely across the intermediacy of the rear side of the back section 15 and is equipped with a pintle 19 projecting from each end thereof, for engagement within the corresponding slots 9 in the side panels 8, (see Figure 2).

60 The cross member 11 on the seat section 10 also has pintles at its ends for engagement within the slots 9 of the side panels 8.

65 It will thus be seen that by lifting the inner end portion of the seat section 10 upwardly, the outer end may be swung downwardly which will result in the lifting of the back section 15 and the final disposition of the parts in the manner shown in Figure 3, the entire structure being disposed within the 70 pocket 6.

75 In Figure 5; as well as Figure 6, a modification of the invention is shown, wherein the supporting wall is denoted by numeral 5'. A pair of guide rods 6'-6' have their ends disposed toward the wall as at 7' and anchored in any suitable manner thereto. The seat section 10' is equipped with the cross member 11' at the underside of its inner end, while a cross member 12' is disposed across the underside of the seat section at its intermediacy. A supporting bar 13' is pivotally interposed between the wall 5' and the seat section 10' by a pivotal connection.

80 Each end of the cross bar 18' on the back of the back section 15' is equipped with an eyelet 19' for receiving the corresponding guide rods 6'. The cross member 11' is also equipped with eyelets 19' at its extremity for receiving the said guide rods 6'. 85 90 95 100

5 The back section 15' is pivotally connected to the inner end portion of the seat section 10' by means of the pivotal connection 17'. By lifting the inner end portion of the sections 10' upwardly, the outer end portion may be swung inwardly, which will result in the lifting of the back section 15' to disclose the parts in substantially the same manner as the parts of the preferred form of the invention 10 as shown contracted in Figure 3.

15 The foregoing invention has many uses and it is obvious that numerous changes in the specific shape, size and materials may be resorted to without departing from the spirit and scope of the invention as claimed hereinafter.

Having thus described my invention, what I claim as new is:

20 1. A foldable chair structure comprising a supporting structure, a seat section, a slideable connection between the inner end of the seat section and the said supporting structure, a back section, a pivotal connection between the back section and the inner end portion of 25 the seat section, and a slideable connection between the said back section and the said supporting structure, the inner end of the said seat section being adapted to be lifted, so that the outer end will swing downwardly and 30 cause the seat section to assume a position on substantially the same plane with the back section.

25 2. A foldable chair comprising a pair of guide rods, a seat section slidably connected at one end to the said guide rods, a back section pivotally connected to the inner end of the said seat section and a slideable connection between the said back section and the said 35 guide rods.

40 In testimony whereof I affix my signature.
HOWARD E. RICE.
